By Attorney Robert W. Jenne

UNITED STATES PATENT OFFICE.

FRANCIS WOOD, OF BROOKLYN, NEW YORK.

DESIGN FOR A PEN-RACK.

SPECIFICATION forming part of Design No. 26,319, dated November 24, 1896.

Application filed September 24, 1896. Serial No. 606,891. Term of patent 7 years.

To all whom it may concern:

Be it known that I, FRANCIS WOOD, a citizen of the United States, residing at Brooklyn, in the county of Kings and State of New York, have invented and produced a new and original Design for Pen-Racks; and I do hereby declare the following to be a full, clear, and exact description of the invention, such as will enable others skilled in the art to which 5 it appertains to make and use the same.

In the drawings, Figure 1 is a front view of the pen-rack. Fig. 2 is a cross-section taken on the line $x-x$ in Fig. 1.

The leading feature of my design consists 15 of a bar of glass, metal, or other heavy material, triangular in cross-section and provided with a series of notches or indentations in each of its angles.

A is the bar, triangular in cross-section, and 20 a are the notches in its angles. These notches

are concave in a longitudinal direction, and their bottoms are rounded and convex at a' in a transverse direction. A concave groove b extends longitudinally along each side of the bar between the notches a .

This device is used as a paper-weight and pen-rack combined, and the pens or pencils rest upon it, as shown at c . This device will prevent the pens or pencils from rolling off a sloping disk.

25 I claim—

The design for a pen-rack substantially as herein described and shown.

In testimony whereof I affix my signature in presence of two witnesses.

FRANCIS WOOD.
